UNITED STATES PATENT OFFICE.

GEORGE W. COPE AND WILLIAM L. BERTRAM, OF DETROIT, MICHIGAN,
ASSIGNORS TO ECONOMY STOVE & MANUFACTURING COMPANY, OF
DETROIT, MICHIGAN, A PARTNERSHIP.

DESIGN FOR A STOVE.

SPECIFICATION forming part of Design No. 36,112, dated October 14, 1902.

Application filed August 21, 1902. Serial No. 120,601. Term of patent 3½ years.

To all whom it may concern:

Be it known that we, GEORGE W. COPE and WILLIAM L. BERTRAM, citizens of the United States, residing at Detroit, in the county of Wayne and State of Michigan, have invented and produced a certain new, original, and ornamental Design for a Stove, of which the following is a specification, reference being had therein to the accompanying drawing, in which the figure is a perspective view of the stove.

The reference-letter A designates the base-section of the stove, which is substantially rectangular in configuration and provided at the corners with the ornamental legs B. Supported on the base is a plain oval body C, capped by the top plate D, which overhangs the body and is surmounted by a scroll ornament E.

Extending up on either side of the lower part of the body from the base and across the body is a scroll-ornamented band F around the door-opening, in which are the substantially rectangular door-frames G, having

cross-bars H and provided with a light involute scroll ornamentation I. These door-frames, with their superimposed scroll, are curved outwardly in vertical section, so as to make, in effect, an enlargement or bulging of the base at that point.

The leading feature of the design is the stove having its ornamental base surmounted by the plain body, having at the front the scroll-ornamented band H, extending up the sides and across the front and inclosing the substantially rectangular door-frames, having cross-bars and an open scroll ornamentation.

What we claim as our invention is—

The ornamental design for a stove substantially as herein described and shown.

In testimony whereof we affix our signatures in presence of two witnesses.

GEORGE W. COPE.
WILLIAM L. BERTRAM.
